Inventor:
Frederick T. Harlan.
By John C. Wiggin
Attorney.

UNITED STATES PATENT OFFICE.

FREDERICK T. HARLAN, OF PLAINVIEW, ILLINOIS, ASSIGNOR OF ONE-HALF TO
EDWARD J. RATZ, OF PLAINVIEW, ILLINOIS.

TOY AMUSEMENT WHEEL.

1,413,850.

Specification of Letters Patent. Patented Apr. 25, 1922.

Application filed May 2, 1921. Serial No. 466,072.

To all whom it may concern:

Be it known that I, FREDERICK T. HARLAN, a citizen of the United States, residing at Plainview, Macoupin County, in the State of Illinois, have invented certain new and useful Improvements in Toy Amusement Wheels, of which the following is a specification containing a full, clear, and exact description, reference being had to the accompanying drawings, forming a part hereof.

My invention consists in the novel construction and combination of parts herein-after particularly described and distinctly claimed.

The object of my invention is to provide a cheap, simple, and instructive wheeled toy that shall be in the form of a miniature amusement-wheel carrying swinging-seats in which dolls or other articles may be carried while the toy amusement-wheel is rotated during the forward or backward movement of the toy upon the floor, walk, or other fixed support.

In the drawings,

Fig. 1 is a side-elevation of my toy.

Fig. 2 is a top plan-view of the same, and

Fig. 3 is a front view of the same, with the tongue or handle shown in cross-section.

The numeral 1 designates a pair of supporting-wheels, which are mounted upon an axle 2 that revolves in bearings 3 in the lower part of opposite platform-supporting brackets 4.

Any suitable material, such as wood, tin, aluminum, or other metal, may be used in manufacturing my invention.

A horizontal platform 5 is fixed upon the upper portions of said brackets 4, and from this platform rise two opposite vertical amusement-wheel supporting standards 6, carrying bearings 7 in which the horizontal shaft 8 of the seat-carrying wheel is mounted to revolve.

Said supporting-wheels 1 are shown in the form of sheet-metal disks, with tires or treads 9 made by turning a bead or flange on the margins of said wheels; but it should be understood that instead of the metallic disk-wheels herein shown I may use any common or well-known spoked-wheels that are at present in use as supporting-wheels for toys or wagons.

One or both of said supporting-wheels 1 should, of course, be fixed on said axle 2, so

that the latter will be positively driven as 55 said wheels roll upon the floor or walk.

A series of combined braces and guards 10 also rise from said platform 5, and have their upper portions curved inwardly and soldered or otherwise attached to the upper 60 portions of the said standards 6, so that the latter will be braced and the seat-carrying-wheel will be protected from breakage or damage when the toy is accidentally tipped over and allowed to fall upon a hard surface.

Said combined braces and guards 10 are arranged to project on all sides beyond the seat-carrying wheel, which will now be described in detail.

A pair of disks or wheels 11, carrying radial arms 12 are fixed opposite each other, with a car or seat-space between them, are on the said wheel-shaft 8 and hanging cars or seats 14 have their vertical end-walls pivotally suspended in said space between said opposite disks or wheels.

Hereinafter I shall use the term swinging cars when referring to the said members 14, as they swing loosely upon the end-pintles of 80 U-shaped reversible passenger guards 15.

Said guards 15 have their pintles 16 pivotally mounted in bearings in the outer ends of the said radial arms 12, and are to be thrown back against or upon the seat-backs 85 17, to permit the entrance or exit of the passengers or dolls 18, Fig. 1.

After the passengers are safely seated upon the benches or seat-boards 19, in said swinging cars 14, the said pivoted or hinged guards 90 15 are thrown forward, over the heads and to a position in front of the passengers, where said guards rest upon inclined seats 20 formed upon the said vertical end-walls of the said swinging cars 14.

A drive-pulley 21 is fixed on said axle 2, and is provided with a groove 22 in its periphery.

A suitable belt 23 engages the said drive-pulley 21 and passes over a grooved pulley 100 24 that is fixed on said horizontal shaft 8, and thereby causes the car-carrying members together with all of the said cars 14, to rotate, as the toy is pulled or pushed on the floor, walk, or upon the ground.

Said belt passes through holes or openings 25 formed in the said platform 5.

A tongue or handle 26 is secured by bolts

or screws 27 to cross-bars 28 that have their ends fastened to the said brackets 4, below said platform 5.

Screws 29 are used to fasten said cross-bars in position.

The operation.

The operation and use of my invention will be entirely clear from the above description, but it may be well to state that the construction is such that the supporting-wheels 1 are not only adapted to support the weight of the entire toy, but that they are also drive-wheels, or traction-wheels, inasmuch as 15 they impart a rotary movement to the movable parts of the amusement-wheel carried by the said platform 5.

The said swinging-cars 14 always maintain an upright position upon the toy, owing to 20 the fact that their center of gravity is far below their pivotal-points, even though the car-carrying parts be rotated quite rapidly, by drawing or pushing the toy along on a supporting surface.

25 *I claim:*

A wheeled-toy, comprising a horizontal platform; ground-wheels on which the said platform is mounted; two vertical supporting standards carrying bearings and rising 30 from said platform; a miniature amusement-

wheel composed of a horizontal shaft mounted to revolve in said bearings of said standards; a pair of disks having radial arms fixed opposite each other and providing a car space between them; U-shaped passenger guards having their pintles pivotally mounted in bearings in the outer ends of the said radial arms; swinging cars mounted to swing loosely upon the end pintles of the said U-shaped passenger guards; a tongue or handle 40 for pulling or pushing the toy along a supporting surface; means for driving said amusement-wheel from one of said ground-wheels when the toy is pulled or pushed upon a supporting surface; and a series of combined guards and braces rising from said platform and arranged to extend on all sides beyond the movable parts of said amusement-wheel to protect the movable parts from injury when the toy is accidentally 45 tipped over or allowed to fall in any direction upon a hard object.

In testimony whereof, I have signed my name to this specification in the presence of two subscribing witnesses.

FREDERICK T. HARLAN.
